UNITED STATES PATENT OFFICE

162,389

COMBINED TRAY, NUTCRACKER BLOCK, AND BOWL

Michael Corpora, Mountain View, Calif.

Application September 7, 1949, Serial No. 4,884

Term of patent 14 years

(Cl. D44—1)

To all whom it may concern:

Be it known that I, Michael Corpora, a citizen of the United States, residing at Mountain View, in the county of Santa Clara and State of California, have invented a new, original, and ornamental Design for Combined Tray, Nutcracker Block, and Bowl, of which the following is a specification, reference being had to the accompanying drawing, forming a part thereof.

In the drawing:

Fig. 1 is a frontal perspective of a combined tray, nutcracker block and bowl showing my new design therefor.

Fig. 2 is top view of the ensemble shown in Fig. 1.

Fig. 3 is an end view of the same as seen from the right in Figs. 1 and 2.

I claim:

The ornamental design for a combined tray, nutcracker block, and bowl, as shown.

MICHAEL CORPORA.
